UNITED STATES PATENT OFFICE.

DON D. MYERS, OF TOLEDO, OHIO, ASSIGNOR TO INDUSTRIAL RESEARCH CORPORATION, OF TOLEDO, OHIO, A CORPORATION OF DELAWARE.

AUTOMATIC SPARK CONTROL.

Application filed June 21, 1920. Serial No. 390,426.

To all whom it may concern:

Be it known that I, DON D. MYERS, a citizen of the United States, residing at Toledo, in the county of Lucas and State of Ohio, have invented certain new and useful Improvements in Automatic Spark Controls, of which I declare the following to be a full, clear, and exact description.

My invention relates to improvements in means for controlling the throttle and the ignition timer of internal combustion motors.

When the usual type of internal combustion motor is subjected to a sudden increase in load and the throttle is opened to restore the motor under increased load to its original speed, the motor pounds and operates inefficiently. By retarding the ignition timer at the time the throttle opening is increased, this undesirable condition may be compensated for, but in order to insure the proper adjustment of the timer and in order to restore the timer to its original position when the motor has recovered its speed, it is very desirable to employ a device which is simple and automatic in operation.

One object of my invention is to automatically adjust the timing of the ignition circuit to make up for a sudden increase in load on the motor when the throttle is quickly opened.

Another object of the invention is to automatically restore the timer of the ignition circuit to its original adjustment at a predetermined time after the timing of the ignition has been retarded.

Other objects and advantages relating to details of construction and economies of manufacture will appear as I proceed with the description of that embodiment of the invention, which for the purpose of the present application I have illustrated in the accompanying drawings.

Referring to the drawings:

Figure I is an elevation partly in section of a preferred form of my invention.

Fig. II is a detail sectional view of a larger scale of the dashpot mechanism shown in Fig. I.

Fig. III is an elevation, partly in section, showing the location of certain parts during the operation of the spark retarding means.

Fig. IV is a section on the line IV—IV of Fig. III, looking in the direction of the

arrows and showing certain details in connection with the timer.

Fig. V is a section along the line V—V of Fig. III, showing the throttle and spark control levers.

In Fig. I the throttle 1 is controlled by the bell crank lever 2 which in turn is operated by the accelerator pedal 3 and restored to closed position by the spring 4. Adjacent to and in the path of the forward end of lever 2 is the bell crank lever 5 for automatically controlling the timing of the ignition. Spring 6 maintains lever 5 drawn toward its normal position as shown in Fig. I. Fig. V indicates more clearly the means by which throttle control lever 2 engages the forward end of ignition control lever 5. Attached to the lower end of ignition control lever 5 is the cylinder 7 within which operates piston 8 attached to one end of the rod 9. The combination of cylinder 7 and piston 8 constitutes a dashpot or fluid actuated means. Rod 9 is linked to the lever 10 of ignition timer 11, as shown more clearly in Fig. IV. The lever 10 shifts the position of one or more contacts, not shown, in a manner well known in the art. Yoke 12 is rigidly supported on one end of rod 9 and is free to slide longitudinally upon the rod 13 which is connected to the manually operated means, not shown, ordinarily provided for adjusting the advance or retard of the spark and which normally remains locked in position. At the end of the rod 13 is rigidly mounted the yoke 14 which is free to slide longitudinally upon the rod 9 and at the same time forms an abutment for one end of helical spring 15 whose other end abuts upon yoke 12. Adjustable collar 16, supported upon the rod 9, provides a means for limiting the travel of yoke 14 upon the rod 9 thus making it possible to place spring 15 under an initial compression.

At one end of the cylinder 7 are provided a series of openings 17, and at the other end, the opening 18 the size of which may be varied by valve 19. The piston 8 is provided with a valve 20 which permits the piston to move more freely toward the openings 17 than toward the opening 18.

The operation of my device is as follows:

The operator of the motor upon encountering a sudden increase in load which decreases the speed of the motor, depresses

pedal 3, deflecting lever 2 to open throttle 1, at the same time engaging the ignition control lever 5, and upon the raising of the same forcing cylinder 7 toward the piston rod 9 whereby air is compressed at one side of the piston and finds egress through the opening 18, and upon the other side of the piston 8 air is rarefied but gradually returns to atmospheric pressure as the result of air passing through openings 17. Before equilibrium can be established in the cylinder 7 by air passing through the openings 17 and 18 the rod 9 is longitudinally displaced and compresses spring 15 at the same time producing a corresponding deflection of the lever 10 in such a direction as to retard the spark. The energy stored in the spring 15 by virtue of this compression is then gradually dissipated in forcing the air through the restricted opening 18, so that a definite period of time is required before the spring 15 can restore the rod 9 to the position it had before the pedal 3 was depressed. The action of the spring 15 in restoring the rod 9 to its original position provides an efficient method of gradually advancing the timing of the spark as the speed of the motor recovers due to the increased supply of fuel through the throttle.

In the form of dashpot shown, the valve 20 permits the cylinder 7 together with lever 5 to return quickly to normal position after the pedal 3 has been released, thereby preparing the ignition control mechanism for a new cycle of operation in less time than would be possible in case the valve 20 were not provided.

The timer is shifted by an amount depending upon the rate of depression of the pedal 3. If the pedal 3 be depressed very slowly, air will readily pass out of the cylinder 7 through the opening 18, and at the same time air will be passing into the other end of the cylinder through openings 17, and piston 8 will remain unmoved by the slight pressure difference between the two sides of the piston. When, however, the pedal 3 is depressed quickly, the difference in pressure between the sides of the piston is sufficient to force the piston forward and compress the spring 15. The amount of shifting which takes place is to a certain extent proportional to the rate at which the pedal 3 is depressed and consequently if the throttle be shifted suddenly to a wide opening, the period during which the timer will remain retarded will be greater than in the case where the throttle is shifted more slowly to this wide opening.

The rate at which the automatic restoring of the timing takes place may be varied by adjustment of the collar 16 upon the rod 9 to vary the stiffness of the spring 15; or by changing the size of the opening 18 by means of the valve 19. By reducing the

size of the opening 18 the air contained between the cylinder and piston will escape more slowly and consequently the spark can be retarded to a greater extent and a greater time will be required to restore the spark to its previous adjustment with reference to the manual ignition control rod 13 than in the case where the opening 18 was relatively large. By increasing the initial compression of the spring 15 the energy stored therein by a quick depression of the pedal 3 will be increased, thus resulting in the spark being retarded to a somewhat less extent and in a more rapid restoration of the spark to its normal adjustment with reference to the control rod 13 than in the case where the compression of spring 15 was relatively small.

Having once adjusted the compression of the spring 15 and the opening of valve 19 to provide the desired control over the spark, if the load on the motor be suddenly increased, thereby resulting in decreased speed, the operator has simply to open the throttle, and the spring 15 in combination with the dash pot mechanism 7, 8 provides automatically a temporary retardation of the spark while the motor accelerates and reaches its normal speed. These adjustments may be so made as provide automatically at each instant the proper timing of the spark to correspond with the speed of the engine at that particular instant, thus relieving the operator from the care incident to the ordinary manual adjustment involved in control devices of the prior art.

I am aware that the particular embodiment of my invention above described, and illustrated in the accompanying drawings is susceptible of considerable variation without departing from the spirit thereof and therefore I desire to claim my invention broadly as well as specifically as indicated by the appended claims.

I claim as my invention:

1. In a system of control for an internal combustion engine, a throttle, an ignition timer having a normal position, means operative upon sudden opening of the throttle automatically to retard said timer, and additional means adapted to restore said timer to normal, the time rate of restoration of the timer to normal position being lesser than the time rate of retardation.

2. In a system of control for internal combustion engines, a throttle, an ignition timer, means operative upon the sudden opening of the throttle to automatically retard said timer, and means in which energy is stored by the operation of said first named means to restore said timer after said first named means ceases to operate within a predetermined time limit, the time rate of the restoration of the timer to normal position being lesser than the time rate of retardation.

3. In a system of control for internal combustion engines, a throttle, an ignition timer, means operative upon the opening of the throttle to automatically retard said timer, means to restore said timer to its original position within a predetermined time limit, and adjustable means for regulating the length of said time interval.
4. In a system of control for internal combustion engines, a throttle, an ignition timer, 10 throttle operating mechanism, a timer operating connection adapted to be actuated by said mechanism to retard the spark when the throttle is opened, said connection including a dash-pot directly and continuously connected therein, and resilient means tending to oppose the retarding of the spark.
5. In a system of control for an internal combustion engine, an ignition timer, a first 20 lever for controlling the flow of gas to said engine, a second lever adapted to be engaged by said first lever for retarding said timer, and means to automatically advance said timer toward its original position after said 25 levers have come to rest, the time rate of the restoration of the timer to normal position being lesser than the time rate of retardation.
6. In a system of control for an internal 30 combustion engine, a throttle controller, and an ignition controller shifted thereby, including means for restoring itself within a predetermined time to the position held before being shifted, the time rate of the 35 restoration of the timer to normal position being lesser than the time rate of retardation.
7. In a system of control for an internal 40 combustion engine, a throttle controller, an ignition timer, and means dependent on the rate of operation of said throttle controller toward open throttle position to shift said ignition timer a variable distance.
8. In a system of control for an internal 45 combustion engine, a throttle, an ignition timer, and coupling means therebetween responsive to a throttle opening to retard and then advance said ignition timer to the position held before being retarded, 50 said advance being accomplished and within a predetermined time, the time rate of the restoration of the timer to normal position being lesser than the time rate of retardation.
- 55 9. In a system of control for an internal combustion engine, an ignition timer, mechanism to retard the timer including a column of fluid, means permitting leakage of said fluid, and a spring coupled to said mechanism and positioned thereupon so as to retard the movement of the mechanism when the timer is retarded.
- 60 10. In a system of control for an internal combustion engine, means to control the flow of gas thereto, an ignition timer, and 65 a coupling therebetween, including an energy storing device and an energy absorbing device to automatically accomplish retarding of said timer momentarily only when the flow of gas is suddenly increased, 70 the restoration of the timer to normal position being accomplished at a different rate than that of the retardation of the timer.
11. In a system of control for an internal combustion engine, means to control the flow 75 of gas thereto, an ignition timer, a coupling therebetween, including an energy storing device and an energy absorbing device to automatically accomplish the retarding of said timer momentarily only when the flow 80 of gas is suddenly increased, and means for varying the rate at which energy is absorbed by said energy absorbing device.
12. In a system of control for an internal 85 combustion engine, a throttle, an ignition timer, a coupling therebetween to retard said timer when said throttle is suddenly opened, means included in said coupling to advance said timer to its original position after said throttle has ceased opening, and 90 means included in said coupling to vary the amount of retardation of said timer for a given rate and amount of opening of said throttle.
13. In a system of control for internal 95 combustion engines, a throttle controller, an ignition timer, and means connected directly and continuously therebetween, including a dash pot, to retard said timer upon the sudden opening of the throttle, and a spring 100 mechanism tending to restore said timer to its original position.
14. In combination, a throttle, mechanism for operating said throttle, a timer lever, manually controlled means for shifting said 105 timer lever, tending to remain fixed after adjustment, automatically controlled means for shifting said lever tending to retard the spark upon the operation of said throttle 110 mechanism to open the throttle, and a resilient connection between said two means tending to oppose relative movement, said automatically controlled means including a column of fluid having provision for leakage therefrom.
- 115 15. In a control system for engines, the combination of a throttle; an ignition timer; common control means for said throttle and timer; a direct and constant connection between the control means and timer; and a yielding element interposed in said connection and adapted to retard momentarily said timer when said throttle is opened.

In testimony whereof I affix my signature.

DON D. MYERS.
